[57] **CLAIM**

The ornamental design for a sweeper housing, as shown and described.

DESCRIPTION

FIG. 1 is a perspective view of a sweeper housing which embodies our design;

FIG. 2 is a front elevational view thereof;

FIG. 3 is a rear elevational view;

FIG. 4 is a left side elevational view thereof, the right side elevational view thereof being a mirror image thereof;

FIG. 5 is a top plan view thereof;

FIG. 6 is a bottom plan view thereof; and,

FIG. 7 is a bottom perspective view thereof.

The broken line showing of the handle in FIGS. 1-4 is for illustrative purposes only and forms no part of the claimed design.

The broken line showing of the handle in FIGS. 1-4 and 7 is for illustrative purposes only and forms no part of the claimed design.
